UNITED STATES PATENT OFFICE.

JOHN F. O'CONNOR, OF CHICAGO, ILLINOIS, ASSIGNOR TO WILLIAM H. MINER, OF CHICAGO, ILLINOIS.

DRAFT-RIGGING FOR RAILWAY-CARS.

1,142,839:

Specification of Letters Patent. Patented June 15, 1915.

Application filed April 11, 1914. Serial No. 831,289.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is, to provide a draft rigging of simple construction and efficient operation.

In the drawings forming a part of this specification, Figure 1 is a side elevation, partly in vertical longitudinal section, of a draft rigging embodying my invention; Fig. 2 is a horizontal section taken on line 2—2 of Fig. 1; Fig. 3 is a cross section taken on line 3—3 of Fig. 1; Fig. 4 is a vertical longitudinal section showing the position of the parts when the draft rigging is in full buff, and Fig. 1 showing the parts in normal position.

Referring to the drawings, the numerals 5—5 represent center sills or parts of the car underframing to which the draft members are secured. The draft members are indicated by the numerals 6—6. The draft members preferably consist of channel-shaped members, to the flanges whereof are secured the upper and lower transverse cover plates 7 and 8, respectively. In preferable construction, a reinforcing member 9, preferably an angle-iron, is longitudinally secured to the upper outer edges of the upper cover plate 7, and is suitably engaged to the adjacent center sill 5. The upper and lower cover plates 7 and 8 are each provided with a vertical opening 10, the said openings registering with each other. The portion 45 of the cover plates forming the forward ends of these openings constitute the front stop-shoulders 12—12, and the portions of the said cover plates forming the rearward end of said opening constitute the rear stop-shoulders 13—13. In preferable construction, the stop-shoulders so formed are reinforced by outwardly disposed members 14—14, preferably angle-irons mounted at the front and rear edges of the openings 10

in the cover plates, and transversely of the 55 cover plates.

The numeral 15 represents the front follower, and 16 the rear follower. Between the followers is mounted a compression resisting member 17, consisting preferably of 60 an upper set of springs 18, and a lower set of springs 19. Each set of springs comprises preferably an outer spring 20 and an inner spring 21 nested therein. The followers are each provided on their inner 65 faces with upper and lower bosses 22 and 23, respectively, about which the ends of the sets of springs are seated. Passing between the followers and between the upper and lower sets of springs is a key 24, secured at its ends within the draft members 6—6.

A draft yoke 25 connects the followers and compression resisting members to the draw-bar 26, the draft yoke being slidingly 75 engaged to the draw-bar by means of a coupler key 27 passing through the draw-bar and through the longitudinally extended slots 28 in the draft yoke, the said slots being sufficiently rearwardly extended to permit the rearward sliding of the coupler key thereon on rearward movement of the draw-bar. As will be understood by those skilled in the art, by the term yoke, which I use in the specification 85 and claims, is meant not only the U-shaped type of yoke shown in the drawings, but all equivalent means serving a similar function for connecting the draw bar with the rear follower so as to pull the latter forwardly under draft, such means sometimes taking the form of links and keys. The ends of the key 27 pass through longitudinally extended slots 29 in adjacent portions of the draft members 6. I reinforce the draft members by providing a separable arm 30 for each, secured to the draft member by means of the rivets 31—31. The said arms 30 are preferably mounted on the outer faces of the draft members as shown in the drawings. 100 The said arms are each provided with perforations 33 for the key 24, and 34 for the key 27. The key 24 is secured at its ends within the draft members, and is prevented from being accidentally displaced preferably by the bolts 35—35 passing therethrough and through adjacent portions of the arm 30. The limbs 36—36 of the yoke are pro-

vided with transverse perforations 37 through which the key 24 passes, the perforations or slots 37 being rearwardly extended to permit the movement of the yoke 5 upon the key 24. In preferable construction, the slots 37 being of such length that when the forward ends of the slots engage against the front edge of the key 24, and the rear follower is in engagement against the 10 rear stop-shoulder, the rear follower will also be in engagement with the rear end of the yoke. Thus in buffing movement of the gear, the rear follower is held against rearward movement by both the rear stop-shoulders and through the yoke by the key 24.

On forward movement of the draw-bar, the yoke is drawn forwardly by the coupler key 27, the rear follower pressing the springs 20 against the front follower 15, which is stopped against forward movement by the front stop-shoulders 14 formed in the cover plates as hereinbefore described. On such forward movement, the yoke slides upon the key 24 within the slots 37 provided in the 25 limbs of the yoke, the rear edge of the key 24 serving as stop to limit the forward compression of the springs.

On rearward movement of the draw-bar, the coupler key 27 slides rearwardly within 30 the slots 28 in the yoke, the draw-bar 26 directly engaging the front follower and compressing the compression resisting members against the rear follower 16, which is stopped against rearward movement by the 35 rear stop-shoulders formed as hereinbefore described, and also by the draft yoke, which is held against rearward movement by the key 24.

I claim:—

1. In a draft rigging for railway cars, the 40 combination with draft members, a draw-bar and draft yoke connected to the draw-bar, of followers, a compression resisting member mounted between the followers, a key secured at its ends in the draft members 45 and passing between the followers, and cover plates, the cover plates being provided with openings to receive the followers and compression resisting members, the portions of the cover plates defining the front and rear 50 ends of the said openings constituting stop-shoulders for the followers, said key supporting the compression resisting member.

2. In a draft rigging for railway cars, the combination with draft members, of upper 55 and lower flat plates secured to the tops and bottoms of said draft members, said plates being provided with vertically aligned openings, said openings being narrower than the distance between the draft members and 60 the front and rear edges of said plate defining said openings constituting front and rear stop shoulders, reinforcing members secured to said plates and located flush with the front and rear edges of said openings, 65 said reinforcing members being shorter than the distance between the draft members, followers mounted within said openings, a stationary key passing between the followers and shock absorbing means located between 70 said followers, said key acting as a limiting stop for said followers.

JOHN F. O'CONNOR.
